Primary Examiner — Rhea Shields(74) *Attorney, Agent, or Firm* — Rumit Ranjit Kanakia(57) **CLAIM**

The ornamental design for a window groove cleaning brush, as shown and described.

DESCRIPTION

FIG. 1 is a front elevational view of a window groove cleaning brush showing my new design;

FIG. 2 is a rear elevational view thereof; and

FIG. 3 is a left elevational view thereof;

FIG. 4 is a right side view thereof;

FIG. 5 is a top side view thereof;

FIG. 6 is a bottom plan view thereof; and,

FIG. 7 is a perspective view of a window groove cleaning brush showing my new design.

The broken lines in the figures are for the purposes of illustrating portions of the window groove cleaning brush, which form no part of the claimed design.
